GAME BOARD

Frank Kohner, New York, N.Y., and Albert Stubbmann,
Franklin Lakes, N.J., assignors to Kohner Bros., Inc.,
East Paterson, N.J.

Filed May 4, 1970, Ser. No. 22,795

Term of patent 14 years

Int. Cl. D21—01

U.S. CL. D34—5

FIG. I

FIG. 3

FIG. 4

FIG. 2

FIG. 5

FIG. 6

FIG. 7

FIG. 1 is a top view of a game board showing our new design;

FIG. 2 is a bottom view of the game board;

FIGS. 3, 4, 5 and 6 are, respectively, front, rear, left side and right side views of the game board; and

FIG. 7 is a view taken along the line 7-7 of FIG. 1.

We claim:

The ornamental design for a game board, substantially as shown.
